LIFT MECHANISM FOR STRIP GUIDES

William C. McBain, Youngstown, Ohio

Application February 4, 1938, Serial No. 188,668

9 Claims. (Cl. 80—51)

This invention relates to guides for directing strip between the rolls of a rolling mill, and in particular, to apparatus for mounting the top guide for movement into and out of cooperative position relative to the bottom guide which is relatively fixed.

Cooperating top and bottom guides have long been used in connection with strip mills, and it has also been proposed to mount the top guide 10 associated with a reversing mill for movement out of operating position, to facilitate inspection of the strip as it leaves the mill. Top and bottom guides are provided on both sides of a reversing mill, the top guide on the entering side being in 15 operative position while the top guide on the exit side is retracted. The object of my invention is to improve upon the mechanisms known heretofore for mounting the top guide for movement into and out of operative position.

20 In accordance with the invention, I provide suspension members pivoted to the top guide and to a suitable support, whereby the top guide is supported for swinging movement. One form of mechanism for retracting the top guide is manually operable and includes a crank and linkage effective on rotation to swing the top guide to up-tilted position. In another form of the invention, power means effects the swinging of the top guide. In both cases, tilting links, pivoted to 25 the top guide and to fixed fulcrums, control the position of the guide as it swings upwardly away from the bottom guide.

A further feature of the invention is that the suspension members on which the top guide is 30 supported are adjustable to compensate for differences in the thickness of the strip or the guide members which have actual contact with the strip. The suspension members also include means whereby the top guide is permitted to yield 35 under excessive upward pressure exerted thereon by the strip entering the mill.

The following detailed description refers to the accompanying drawings illustrating both the manually operable and power-operated forms of 40 the invention. In the drawings:

Figure 1 is a plan view of my manually operable guide-lifting mechanism, the housings of the mill on which it is mounted being shown in section; 45

Figure 2 is a sectional view taken on the line II—II of Figure 1;

Figure 3 is a view similar to Figure 1, showing the power-operated form of guide-lifting mechanism; 50

Figure 4 is a view partly in section along the line IV—IV of Figure 3 with parts in elevation.

Referring now in detail to the drawings and for the present to Figures 1 and 2, the invention is adapted to be installed upon a rolling mill comprising housings 10 and 11 having work rolls 12 and backing rolls 13, journaled in chucks disposed in the housing windows, all in the usual and well known manner. The details of the mill may be varied within wide range limits, are not 10 part of the present invention, and therefore, require no further description.

Top and bottom guides, indicated generally at 14 and 15, cooperate to direct a strip passing therebetween into the bite of the rolls 12. The 15 bottom guide 15 is carried on a so-called separator 16, which is merely a shelf-like member extending between the housings 10 and 11. The bottom guide 15 comprises a guide proper, shown at 17, formed of wooden members secured to 20 cross pieces in the form of channels 18. A guide frame composed of longitudinal members 19 and side plates 20 rests on an adjusting wedge 21, positioned in a suitably shaped recess in the separator 16. An adjusting screw 22, threaded 25 through a thrust bearing 23 on the wedge and into a tapped hole on the separator facilitates adjustment of the wedge. Additional adjusting screws 24, 25, and 26 permit adjustment of the 30 guide frame and guide proper.

While the details of the bottom guide have been described for the sake of clearness, it is to be noted that any suitable form of bottom guide construction may be employed as the details thereof have no relation to the mounting of the 35 top guide wherein the present invention particularly resides.

The top guide, indicated generally at 14, also includes guide members 27 which have actual sliding contact with the strip as it enters the 40 mill. These members are preferably of wood and are secured to cross pieces 28. The assembled guide members are carried on a frame composed of longitudinal members 29 and side plates 30. A forward cross bar 31 is secured to the ends of 45 the longitudinal members 29 and side plates 30 and bears on the forward channel 28. A similar cross bar 32 is adjustable relative to the rear or outer ends of the members 29 and 30 and bears on the rear channel 28. An adjusting screw 33 50 has a thrust bearing 34 on the cross bar 28 and engages the rear cross bar 32 to adjust the guide proper 17 to such a position as to provide suitable clearance between same and the work roll 12. Adjusting screws 35 and 36 are threaded into 55

toothed segment 100, secured to the housing 10. Movement of the shaft 108, as in the case of the corresponding structure of Figures 1 and 2, causes vertical adjustment of the top guide 18. 5 It will be apparent from the foregoing description and explanation that the invention comprises a simple yet highly effective mechanism for operating the movable top guide of a strip mill from cooperative relation with the bottom guide 10 to a retracted position such that it does not interfere with observation of the strip leaving the mill. It will be understood, of course, that similar operating mechanism will be provided for the top guides on both sides of the mill and that 15 they will be appropriately operated to move the top guide on the entering side into cooperative position with the bottom guide and at the same time to move the top guide on the exit side to the dotted line position shown in Figure 2 or 4. 20 Relatively little effort is required to operate the manually operable lift, while in the case of the power-operated lift, it is only necessary to manipulate the control valve. The adjustment of the top guide, effected by rotation of the shaft 25 supporting the guide-suspending members, permits the spacing between the top and bottom guides to be varied to accommodate different thicknesses of strip, as well as to compensate for wear in the guide members themselves, which are 30 usually of wood. The thumb screws 35 and 36 hold the guide proper 27 against the guide frame 30, which is pivoted on the shaft 40 and is free to swing thereon through a small arc. By this means, the pressure of the upper guide is suitably distributed on the strip when it is being 35 rolled. The compressible linkage shown in Figure 2 for supporting the top guide permits the latter to yield upwardly when an exceptionally thick portion of the strip enters the guides. The 40 tilting links insure that the rear end of the top guide is sufficiently elevated when the guide is retracted, and the extent of this elevation may be adjusted by means of the turn buckles incorporated in the links.

45 Although I have illustrated and described but two preferred forms of the invention, it will be understood that changes in the construction and operation disclosed may be made without departing from the spirit of the invention as set forth in the appended claims.

50 I claim:

1. The combination with a rolling mill having spaced housings and top and bottom strip guides disposed therebetween, of lift mechanism for said 55 top guide comprising hangers pivoted to the top guide and to a cross shaft extending between said housings above said top guide, a second cross shaft extending between said housings above said top guide and having a crank arm, and a link 60 connected to said top guide and said crank arm whereby rotation of the latter causes said top guide to tilt upwardly and rearwardly and swing said hangers on said first mentioned shaft, said hangers including telescoping spring-urged members 65 for relieving excess upward pressure exerted on said top guide by the strip passing between the guides.

2. Guiding mechanism for directing strip between the rolls of a rolling mill, comprising a 70 relatively fixed bottom guide, a top guide movable into and out of cooperative relation with the bottom guide, suspension members pivoted to the top guide, a support for said members above the top guide, a crank arm, means above the top 75 guide supporting said arm for rotation, a link pivoted to said arm and the top guide whereby the top guide is swung upwardly and rearwardly at the rear.

link pivoted to said arm and the top guide whereby the top guide is swung upwardly and rearwardly to a position out of cooperative relation with the bottom guide on rotation of said crank in one direction, and a tilting link having one 5 end pivoted to a fixed fulcrum and the other end pivoted to said top guide at a point spaced from that at which the suspension members are pivoted thereto, and effective to tilt the top 10 guide upwardly at the rear.

3. Guiding mechanism for directing strip between the rolls of a rolling mill, comprising a relatively fixed bottom guide, a top guide movable into and out of cooperative relation with the bottom guide, suspension members pivoted to the 15 top guide, a support for said members above the top guide, a crank arm, means above the top guide supporting said arm for rotation, a link pivoted to said arm and the top guide whereby the top guide is swung upwardly and rearwardly 20 to a position out of cooperative relation with the bottom guide on rotation of said crank in one direction, and means whereby said support may be adjusted toward and from said bottom guide.

4. Guiding mechanism for directing strip between the rolls of a rolling mill, comprising a relatively fixed bottom guide, a top guide movable into and out of cooperative relation with the bottom guide, suspension members pivoted to the 25 top guide, a support for said members above the top guide, a crank arm, means above the top guide supporting said arm for rotation, a link pivoted to said arm and the top guide whereby the top guide is swung upwardly and rearwardly 30 to a position out of cooperative relation with the bottom guide on rotation of said crank in one direction, said support comprising a shaft having eccentrics on which said suspension members are journaled, and means for angularly adjusting said shaft.

5. Guiding mechanism for directing strip between the rolls of a rolling mill, comprising a relatively fixed bottom guide, a top guide movable into and out of cooperative relation with the bottom guide, suspension members pivoted to the 35 top guide, a support for said members above the top guide, a crank arm, means above the top guide supporting said arm for rotation, a link pivoted to said arm and the top guide whereby the top guide is swung upwardly and rearwardly 40 to a position out of cooperative relation with the bottom guide on rotation of said crank in one direction, said support comprising a shaft having eccentrics on which said suspension members are journaled, and means for angularly adjusting said shaft.

6. The combination with a rolling mill having spaced housings and top and bottom strip guides disposed therebetween, of lift mechanism for said top guide, comprising hangers pivoted to the top guide on an axis intermediate the ends thereof and to a cross shaft extending between housings above said top guide, a retracting link pivoted to 45 said top guide substantially at said axis, and a second link pivoted to said top guide at a point spaced from said axis and to a fixed fulcrum, whereby said guide tilts upwardly and rearwardly 50 on retraction.

7. Guiding mechanism for directing strip between the rolls of a rolling mill, comprising a relatively fixed bottom guide, a top guide movable into and out of cooperative relation with the bottom guide, suspension members pivoted to the 55 top guide, a support for said members above the top guide, a crank arm, means above the top 60 guide supporting said arm for rotation, a link pivoted to said arm and the top guide whereby the top guide is swung upwardly and rearwardly 65 to a position out of cooperative relation with the bottom guide on rotation of said crank in one direction, and a tilting link having one end pivoted to a fixed fulcrum and the other end pivoted to said top guide at a point spaced from that at which the suspension members are pivoted thereto, and effective to tilt the top 70 guide upwardly at the rear.

- top guide along a transverse axis, a support for said members above the top guide, a retracting link pivoted to the top guide, and a second link pivoted to said top guide at a point spaced from said axis and to a fixed fulcrum, whereby the top guide is swung upwardly and rearwardly to a position out of cooperative relation with the bottom guide on retraction by said link.
8. Apparatus for movably supporting a top guide adapted to cooperate with a relatively fixed guide in directing strip between the rolls of a mill, said apparatus comprising a shaft extending parallel to said rolls, a link pivoted to said top guide, a second shaft parallel to the first mentioned shaft, a crank on said second shaft to which said link is pivoted, eccentrics mounted on
- 5
- 10
- 15

said first mentioned shaft carrying bearings suspending said guide, means on said second shaft suitably arranged for rotating it to one of two selected positions, and means for holding said crank in a selected position.

9. Apparatus for supporting a top guide for a rolling mill comprising a swingable hanger pivoted to the guide along a transverse axis intermediate the ends thereof, a link pivoted to the guide for swinging the guide on its hanger, and 10 a second link pivoted to said guide at a point spaced from said axis whereby to effect angular movement of the guide on swinging thereof with said hanger.
